CLOSURE CAP FOR RECEPTACLES

Herman Lewin, Eosmalen, Netherlands

Application September 12, 1936, Serial No. 100,568
In the Netherlands September 23, 1935

1 Claim. (Cl. 215—38)

The invention relates to a capsule for a bottle or similar vessel, which is constructed in such a manner that it has a particularly simple smooth exterior, that it can be fixed in a convenient manner on a bottle as well as being removable therefrom with the application of small force, and that it is especially suitable for bottles the contents of which are under high pressure.

The capsule according to the invention is especially intended for a bottle of the usual kind, the neck of which is provided with an enlargement or swelling.

The invention is explained in greater detail with reference to the drawing.

15 In this,

Fig. 1 shows on enlarged scale a vertical section of the capsule according to the invention, provided with an insertion disc of the usual form, and arranged on a bottle neck which is represented in side elevation.

Fig. 2 shows the same capsule as illustrated in Fig. 1, in the position during the fixing of the capsule on the bottle neck.

Fig. 3 shows the same capsule as illustrated in Fig. 1 after this has been fixed on the bottle neck.

Fig. 4 shows likewise on enlarged scale a side elevation of the capsule according to Fig. 1 manufactured in heavier material, which is provided on the edge with one or several incisions extending in the axial direction.

Fig. 5 shows finally a form of construction, likewise on enlarged scale, providing a screwed closure.

The form of construction of the capsule 1 according to Fig. 1 has a rolled-up part 8 which forms the end of an outwardly bent-over part 7 of the capsule jacket 6, the part 7 forming with this jacket a V-formation.

The manner of fixing this capsule will also be clear without any difficulty. After the movement of the pressing block 13 in co-operation with the pressure member 15 the ductile edge of the capsule, after the capsule has been placed on the neck 5 of the bottle, is pressed downwards and inwards and thereby permanently bent over so that the bent-over part 7 is flattened out from the upright position more and more to the front as illustrated in Fig. 2, whereupon finally, as shown in Fig. 3, by the action of the straight conical expanding hollow inner part 14 the bending operation proceeds until, with the bottle 4 in the upright position, the bent-over part 7 lies horizontally.

The straight conically expanding hollow inner part 14 of the pressing block, according to the

invention, may be provided preferably with longitudinal grooves or ribs which on pressure being applied to the pressing block, penetrate into the bent-over capsule edge. Since these grooves or ribs may have a different cross-section according to the indentations which are desired to be formed in the bent-over capsule edge (they are not illustrated in the drawing, since their eventual shape will be clear without being illustrated).

Although in Figs. 1 to 3 capsules with an uninterrupted circumferential edge are illustrated, these may also be constructed with an interrupted circumferential edge. According to Fig. 4 the bent-over edge of the capsule 1 is provided with one or several incisions 9 extending in the axial direction. These forms of construction have for their object to facilitate fixing of the capsules on the bottle as well as the removing them therefrom, when harder or thicker material is employed.

The manner of fixing the capsule is also suitable for clamping screw closures tightly on bottles, wherein a lower part remains on the bottle neck, while the upper part may be screwed off and can be screwed on again, so that on this account it may continue to act as the closure. Fig. 5 shows such a screw closure 10 which is provided with a draw tongue 11 and with lines of rupture 12, by the aid of which the capsule can be opened. The bent-over edge may be constructed as represented by the construction represented in Fig. 1. Instead of a tongue, perforations without a tongue may be provided.

Since the capsule according to the invention is manufactured of very thin material, it can easily be removed from the bottle. It likewise has a fine external appearance owing to its simplicity, whereby it may be made in different colours, or can be provided with one or more embossed advertisement signs.

The capsule, besides being used on bottles manufactured for this purpose, may be suitably formed for existing bottles.

Experiments have shown that the closure with capsules according to the form of construction shown in Fig. 1 are able to easily withstand a pressure up to twelve atmospheres, without suggestion of leakage of the sealing or of an escape of the gases present in the bottle.

What I claim is:

A cap for closing the opening in the neck of a bottle having an annular enlargement on the outer part of the neck, comprising a relatively thin metal cap having a top portion adapted to cover the opening and a skirt adapted to ex-

tend downwardly over the neck of the bottle, the lower end of the skirt having a curled portion formed by rolling the skirt outwardly and upwardly sufficient to provide more than one complete turn with the edge of the metal facing away from the downwardly extending portion of the skirt, said rolled metal forming with the skirt a V-shaped bead having an outer portion extending upwardly along the skirt, said bead being formed at such a distance from the top portion that all of the rolled metal is above the enlarge-

ment when the cap rests in an unattached manner on the bottle neck, whereby the cap may be secured over the bottle neck by moving the bead downwardly and inwardly under the enlargement to partly unroll the metal bead and cause the outer portion of the V-shaped bead to be arranged substantially horizontal, and the metal rolled in the bead being sufficient to provide more than a complete turn after the cap is secured on the neck of the bottle.

HERMAN LEWIN. 10
